LOAD RESPONSIVE RECOIL SNUBBER

Ernest G. Goodwin, Roanoke, Va.

Application January 11, 1936, Serial No. 58,734

17 Claims. (Cl. 105—193)

This invention relates to railway snubbers particularly for freight cars having helical springs, and has for its primary object the provision of a simple snubber which acts chiefly to damp the recoil of the springs.

Another object is to provide simple snubbing mechanism which is incorporated in a bolster that may be substituted for bolsters on existing trucks and/or interchanged therewith.

10 A further object is the provision of a snubber which exerts a damping action that increases with increase of load.

A still further object of my invention is the provision of a simple snubber which is positive 15 in its action and automatically takes up for wear.

A still further object is to utilize the necessary vertical guiding surfaces between the sprung and unsprung parts as combination guide and friction surfaces.

20 These and other objects of the invention will be apparent from the following description of a preferred embodiment illustrated in the drawings in which:

Figure 1 is a partly sectional side elevation of 25 a railway truck equipped with my invention, the view being taken on line 1—1 of Figure 2.

Figure 2 is a partly sectional plan view taken substantially on line 2—2 of Figure 1.

Figure 3 is a side elevation of the fulcrum 30 element.

Figure 4 is a vertical cross section taken on line 4—4 of Figure 3.

Figures 5, 6 and 7 are respectively side elevation, plan view and vertical cross section of the 35 wedge used in the snubber.

Figure 8 and 9 are side and front elevations of the arm or equalizer.

As will be seen in Figure 1 my invention is 40 adapted for any standard truck having the usual side frame 10 with a bolster opening 11 bordered by the columns 12 and carrying the usual spring plank 13 on which are placed the springs 14 seated on bottom spring cap 15. The columns 12 are preferably provided with liners 16 of any known type.

45 The bolster 18 differs from the usual standard construction only at the ends where one or both side walls 20 and 21 slope inward from the bottom wall 23 to form pockets 24 and 25 for receiving the snubbing wedges 27 which are preferably identical and interchangeable. The top wall 30 is preferably of about standard bolster width so as to provide ledges 31 and 32 which project over the pockets and thus to a considerable extent keep dust and dirt from the coop-

erating surfaces 33 and 34 of the wedge and wall. As shown in Figure 2 the bolster ends are provided with the usual flanges 36 to limit the transverse bolster movement and these flanges also form the substantially vertical end walls 38 of 5 the wedge pockets which end walls preferably converge slightly inward.

The sloping side walls 20 and 21 of the bolster are apertured as at 40 for accommodating the wedge engaging arm 41 of the lever member 43 shown best in Figures 1, 8 and 9. The other arm 45 of the lever is operably connected as by a spring seat 46 with a wedge operating spring 48, the bottom wall of the bolster being apertured as at 50 for loosely receiving said spring seat. 15 Transverse bosses or ribs 51 are provided on top of the lever for receiving and centering the fulcrum bar 52 (Figures 1, 3 and 4) and similar means 54 are provided on the under side of the top bolster wall 30 for receiving the upper side 20 of the bar. The fulcrum bar and the levers are diagonally positioned in the bolster and with respect to the rectangularly arranged nest of four springs but the arrangement may be changed to accommodate a different number and different 25 arrangement of springs. Due to the diagonal position of the levers the wedge engaging end 56 of the arm 41 is preferably oblique to the lever axis. The cylindrical surface 57 on the end 56 provides a roller engagement with the surface 58 30 at the bottom of the central opening 59 in the wedge which opening roughly registers with the large opening 40 in the bolster wall.

The fulcrum bar 52 is in effect a central section of a cylinder since it has rounded edges both 35 in the notches 60 and 61 for receiving the lever arms and on the projections 62 and 63 for engaging the upper wall of the bolster between the ribs 54. It will be noted in Figures 3 and 4 that the notches 61 are considerably deeper than the notches on the opposite edge, the reason for this being to provide an easy adjustment which consists simply in inverting the fulcrum thus in effect increasing or decreasing the depth of the fulcrum bar, it being understood that only the 40 notch portion engages the levers and only the 45 projections engage the bolster.

The angle which the bolster engaging face 33 of the wedge 27 makes with the vertical friction face 65 determines the amount of snubbing that 50 may be had and the sharper the wedges, the less force required of the lever to bring the shoes into action, thus a relatively small inside coil spring 48 serves the purpose for the mechanism illustrated in Figure 1. The other springs 14 of the 55

set may also be provided with inside coils where the size of the cars require them and these coils may be added without affecting the operation of the snubbing mechanism.

- 5 The operation of the invention will be readily appreciated from a study of the drawings. As the bolster moves down it tends to leave the wedges and thus prevents excessive pressure against the columns but the inside coil spring 48
 10 reacting thru the lever 43 causes the wedges to follow the bolster by forcing the wedges down in proportion to the amount of compression of the springs thus causing some snubbing on each downward motion of the bolster. However, on
 15 the rebound the sloping bolster walls 20, 21 tend to wedge the shoes apart, increasing the pressure on the columns while at the same time the springs 48 continue to act thus causing a much larger snubbing action than occurs when the springs
 20 are compressed. In the embodiment illustrated there will be substantially 70% of the snubbing on the recoil and 30% during compression which is the desired proportion. It will be appreciated that the snubbing action varies with the load
 25 since the coil 48 exerts a force at all times in accordance with its compression.

Although I have shown a snubbing wedge on each side of the bolster it will be seen that a single wedge, due to its reaction, would create
 30 pressure against both columns and thus secure the maximum or same snubbing area. However, I prefer the design shown with two shoes as it makes it easier for the bolster to adjust itself as the car truck passes over vertical curves
 35 or where the side frame and car body rock longitudinally with respect to each other. Figure 2 shows my preferred arrangement of levers and wedges but it will be obvious to those skilled in railway car design that my invention may
 40 be incorporated in the truck in about as many different ways as there are different arrangements of springs.

While I have shown the sloping side of the wedge and adjacent bolster wall as flat, either
 45 of these faces may be crowned to insure perfect seating of the wedge against the column through a slight rocking action. In practice, however, the flat faces are preferred unless the metals are very hard.

50 The vertical portion 68 of the wedge may be termed the shoe proper and as is well known in the art may be separately attached to the wedge portion or may be integral therewith as shown herein.

55 What I claim is:

1. In a car truck, a side frame, springs on said side frame, a bolster supported on said springs and means movable with and in part carried within the bolster for frictionally engaging the side frame, said means including a lever for utilizing the recoil action of some of said springs to vary said frictional engagement with a force proportional to the recoil force of said springs.

65 2. In combination with a bolster end having in one side a wedge-shaped pocket pointing downward, a wedge in said pocket having one face vertical for engaging a column and linkage in the bolster end having a part arranged to engage a bolster supporting spring and having another part engaging said wedge and tending to move it downward with respect to the bolster when said linkage is acted upon by said supporting spring.

70 3. A bolster end having an apertured bottom wall, said aperture adapted to register with a

bolster supporting spring, an apertured side wall sloping inward and upward from one side edge of the bottom wall thereby adapted to cooperate with the vertical face of a side frame column to form a downwardly pointing wedge receiving pocket, a lever having its ends located respectively in said apertures for engaging said spring at the bottom wall and a wedge member at the side wall and fulcrum means for said member carried by the bolster end.

4. In a car truck, a sprung member, an unsprung member; one of said members having a vertical wall adjacent the other member, a friction face on said wall, said other member having a sloping wall forming with said vertical 15 wall a downwardly pointing wedge-shaped pocket, a wedging means in said pocket having a friction face engaging said first mentioned friction face and spring-pressed rocking means movable with said sprung member for moving said wedging means downward with a force that varies with the compression of the springs supporting the sprung member, whereby the rebound of the sprung member is snubbed with greater force at the beginning of its upward movement than at 25 the end of said movement.

5. In a car truck, a bolster, springs supporting said bolster on the truck, a side frame having means for guiding said bolster, said means and said bolster having adjacent walls, one of said walls being vertical and having a friction face, the wall proximate to said vertical wall being sloped to form therewith a downwardly pointing wedge-shaped pocket, a wedge in said pocket having a vertical friction face engaging the first mentioned friction face and acting therewith to snub the movement of the bolster, said wedge being so arranged as to be urged by action of said friction faces to decrease the wedging engagement as the bolster moves downward, a rigid member fulcrumed on the bolster and spring-pressed to urge the wedge downwardly into the pocket with a force that increases and decreases with load increase and load decrease respectively, whereby as the bolster moves downwardly a small 45 but increasing snubbing action is produced and as the bolster rebounds the wedge is moved into wedging engagement both by the spring action and the frictional action to thus produce a great snubbing force which decreases as the 50 bolster moves upward.

6. In a car truck, a bolster spring supported on said truck, said truck including a side frame having spaced columns for guiding the bolster as it moves up and down, wedges on each side 55 of the bolster adapted to be moved by the bolster into wedging engagement with the columns and bolster upon the upward movement of the bolster and to be urged out of wedging engagement by the downward movement of the bolster, wedge 60 springs, and power translating means movable with the bolster and engaging said springs and said wedges to increase the wedging engagement in proportion to the compression of all the springs, whereby the rebound of the bolster is 65 snubbed with greater force than the movement in the opposite direction, and such rebound snubbing is greater at the beginning of the upward movement than at the end of such movement, snubbing the bolster movement in accordance with said wedging engagement, and mechanism including spring means tending to increase said wedging engagement in accordance with the compression of the bolster springs.

7. In a car truck, a bolster spring-supported 75

5 on said truck, said truck including a side frame having spaced columns for guiding the bolster as it moves up and down, wedges on each side of the bolster adapted to be moved by the bolster into wedging engagement with the columns and bolster upon the upward movement of the bolster and to be urged out of wedging engagement by the downward movement of the bolster, and a lever fulcrumed on the bolster and transmitting the force of said spring means to the wedges.

10 the force of said spring to move the bolster.
15 8. In a car truck, a bolster spring-supported on said truck, said truck including a side frame having spaced columns for guiding the bolster as it moves up and down, wedges on each side of the bolster adapted to be moved by the bolster into wedging engagement with the columns and bolster upon the upward movement of the bolster and to be urged out of wedging engagement by the downward movement of the bolster, said 20 wedges having friction surfaces for snubbing the bolster movement in accordance with the wedging engagement, and a lever arranged to be acted on at all times by one of the springs supporting the bolster, said lever engaging one of 25 said wedges to maintain a wedging engagement proportional to the compression of the bolster springs.

Spring.
9. In a car truck, a bolster, springs for supporting said bolster on the truck, said truck including a side frame having spaced columns for guiding the bolster as it moves up and down, shoes slidable on the columns and movable with the bolster to snub the spring action, a wedge between one side of the bolster and the proximate 30 shoe, and means actuated by part of said springs to urge said wedge into wedging engagement in accordance with the movement of the bolster to thus create pressure of the shoes on said columns, said wedge being acted on by the bolster in its 35 downward movement to decrease said wedging engagement and being acted on by the bolster in its upward movement to increase said wedging engagement whereby the greatest amount 40 of snubbing occurs on the rebound of the bolster.

45 10. The device of claim 9 in which said means includes a lever adapted to be operated by said part of said springs to act on said wedge as recited.

11. The device of claim 9 in which is provided
50 a spring seat for one of said springs and in
which said means includes a lever pivoted on
the bolster and having one arm engaging one of
said wedges and the other arm carrying said
spring seat whereby the total force of said one
55 spring acts on the lever to operate the wedge.

12. A self-snubbing bolster adapted to replace the usual standard bolster carried by a nest of coil springs comprising a bottom wall for resting on said springs, said wall having two apertures 60 therein in place of the usual spring seat for two of said springs, a spring seat loosely carried in each of said apertures, a top wall spaced above said bottom wall, two side walls sloping upward and inward from the edges of the bottom wall 65 and joining the top wall, wedges carried on said sloping walls, two levers pivoted in the bolster and each having one arm projecting through the side walls for engaging said wedges and the other arm carrying said spring seats in the 70 bottom wall whereby when said bolster is inserted

in a car truck two of the springs act on said wedges to cause the same to create a snubbing action.

13. In a car truck, a spring supported bolster having sloping side walls at its ends, a side-frame having column faces opposite said sloping walls, said walls cooperating with said column faces to form wedge receiving pockets, snubbing wedges in said pockets and having limited vertical play therein, snubbing springs on the side-frame and levers pivoted on the bolster end and engaging the respective wedges, said levers also engaging the snubbing springs and tending to be turned thereby about their respective pivots to urge the wedges into said pockets to create a snubbing action as the bolster moves up and down.

14. In a car truck, a side frame, springs on said side frame, a bolster supported on said springs, snubbing shoes loosely carried by the bolster for frictionally engaging the side frame to produce a spring damping action, lever means pivotally carried by the bolster for transmitting the force of some of said springs to said shoes to maintain said damping action, and means on the bolster for adding to the damping action as the bolster rebounds and for subtracting from the damping action as the bolster moves downward. 25

15. A bolster having a spring seat on its bottom surface adjacent one end, said end having on one side a column facing surface sloping upwardly and inwardly from the lower portion containing the spring seat, whereby when the bolster is in operative position in a car truck having the usual side frame the sloping surface of the bolster end cooperates with a column of the side frame to form a downwardly pointed wedge-shaped pocket for receiving a downwardly pointing wedge-shaped snubbing member, and an integral ledge projecting from the bolster over the top of said pocket to prevent dirt and dust falling into the pocket.

16. In a car truck, a side frame having a bolster opening and friction surfaces on the sides of said opening, springs on said side frame, a bolster supported on said springs, friction shoes carried by the bolster for slidably engaging said friction surfaces and means carried by the bolster for forcing said shoes against said surfaces with a greater force at the beginning of the upward movement of the bolster than at the end of its upward movement, said means including downwardly pointing wedge mechanism and lever mechanism engaging said wedge mechanism, and a spring member engaging the side frame and said lever mechanism. 45 50 55

17. In a car truck, a side frame having a vertical column, a spring supported bolster, means for constraining said bolster to move in a vertical path adjacent said column upon the contraction and expansion of the springs, and means carried by the bolster including tilting mechanism resiliently biased with respect to said side frame and downwardly pointing wedge mechanism rockingly engaged thereby for frictionally engaging the column, to retard the upward vertical movement of the bolster with a force that decreases as the bolster moves upward. 60 65
